UNITED STATES PATENT OFFICE

1,932,728

VALVE LIFTER

Ludwig B. Glantz, Minden, Nebr.

Application August 16, 1932. Serial No. 629,077

1 Claim. (Cl. 29—86.3)

This invention relates to so-called valve lifters of the type adapted to compress a valve spring sufficiently to permit the locking pin to be readily extracted so that the valve may be quickly removed; and the nature of the present invention together with its numerous objects and advantages will be best understood from a study of the following description, taken in connection with the accompanying drawing wherein:

10 Figure 1 is a side elevational view illustrating the valve lifter as applied to the valve spring of an engine, certain parts of the lifter being broken away and shown in section.

15 Figure 2 is a side elevational view with the lifting arm in a down position and the valve spring compressed.

Figure 3 is a top plan view of the device.

Referring more in detail to the drawing, it will be apparent, that the device comprises a stanchion or supporting rod 5 that has a lower end adapted to be inserted in the spoke opening 6 of the head 7 of the internal combustion engine.

An arm 8 is also provided, and the same equipped with side webs 8a that merge into projections 8b; and the projections 8b receive therebetween an upper portion of the rod 5 and are pivoted to said rod as at 9. At its free end the arm 8 is bifurcated to provide a pair of arm extensions 10.

30 An actuating lever 11 is pivoted at one end as at 12 to the ears or extensions 8b adjacent the free ends of said ears or extensions and adjacent said pivoted end the lever 11 is provided with a cam head 11a which is adapted to work in the space between the ears or extensions 8b, with its working edge adapted to engage the proximate side of the supporting rod 5 so that by the action of the lever 11 arm 8 may be raised and lowered.

40 The operation of the device is as follows: The lower end of the stanchion or support rod 5 is placed within an opening 6 usually provided in a cylinder 7 as aforementioned and the outer or free end of the arm 8 is engaged with the washer

usually provided in the upper end of the valve spring 7a. The lever 11 which is normally in the position shown in Figure 1 is then rotated in a clockwise direction, and with the cam 11a on the end of the lever working against the side of the rod 5, said rod 5 will be caused to bind within the opening 6 while at the same time arm 8 will be caused to swing downwardly to the position shown in Figure 2 and thereby compress the spring 7a; and when the spring 7a has been compressed sufficiently the usual locking pin 7b may be inserted into or withdrawn from the transverse opening, as the case may be, provided in the valve stem 7c.

It will be noted that when the flattened face 65 of the cam head 11a is engaged with the supporting rod 5, the parts will remain in the position shown in Figure 2 until the operator has completed the assembling or disassembling of the valve parts.

70 Even though I have herein shown and described the preferred embodiment of the invention, it is to be understood that the same is susceptible of further changes, modifications and improvements coming within the scope of the 75 appended claim.

Having thus described my invention, what I claim as new is:

A valve lifter comprising a fulcrum post having an end adapted for insertion in the bolt hole 80 of an engine cylinder head, an arm having a broad flat end, and a longitudinally tapering end, and being also provided with side flanges merging at the smallest end of the arm into opposed angularly disposed ears pivoted to the fulcrum 85 post, a lever pivoted adjacent one end thereof between said ears adjacent the free ends of the latter, and being also provided at said one end with a head to engage the fulcrum post for depressing said arm, and said arm at the first 90 named end thereof having a valve stem receiving notch.

LUDWIG B. GLANTZ.
